UNITED STATES PATENT OFFICE.

ROBERT WILLIAM JOHNSON, OF PITTSBURGH, PENNSYLVANIA, ASSIGNOR TO ROBERTS AND SCHAEFER COMPANY, OF CHICAGO, ILLINOIS, A CORPORATION OF ILLINOIS.

PICKING SCREEN.

Application filed March 13, 1922. Serial No. 543,143.

To all whom it may concern:

Be it known that I, ROBERT WILLIAM JOHNSON, a citizen of the United States, residing at Pittsburgh, in the county of Allegheny and State of Pennsylvania, have invented a certain new and useful Improvement in Picking Screens, of which the following is a specification.

My invention relates to a screening and picking device, and particularly for a coal-handling device which is adapted to screen and grade coal and to permit various grades of the coal to be picked during the grading and the conveying consequent thereto. Other objects of my invention will appear from time to time in the course of the specification.

I illustrate my invention more or less diagrammatically in the accompanying drawings, wherein—

Fig. 1 is a plan view of the screen and picking table.

Fig. 2 is a section on the line 2—2 of Fig. 1;

Fig. 3 is a section on the line 3—3 of Fig. 2;

Fig. 4 is an enlarged side view, with parts in section, of the central portion of the device;

Fig. 5 is a view of the actuating means, and

Fig. 6 is a section on the line 6—6 of Fig. 1.

Like parts are illustrated by like symbols throughout the drawings and specifications.

A is any suitable supporting structure having thereon the track or tracks A¹, and being supported, for example, by the uprights A² over a plurality of railroad tracks, which lie preferably at right angles to the working axis of the screen.

B is the lower deck of a balanced reciprocating screen which is supported on the tracks A¹, as by the rollers B¹. It has a closed bottom, B², which is broken at various points by any suitable removable gates, B³, B⁴ and B⁵, which overlie, respectively, the delivery chutes B⁶, B⁷ and B⁸. The deck B terminates in an inclined chute B⁹ adapted to deliver, for example, to any suitable conveying means B¹⁰, or directly to the railroad car X.

Overlying the deck B, and adapted to be reciprocated in opposition thereto, or in al-

ternation therewith, is the upper deck C, mounted, for example, on the roller C¹⁵ on the brackets C²⁰. The deck C has a bottom C¹ broken by the screen section C². Beyond this section is a gate C³ overlying the gate B³ in the lower deck. Above the level C¹ is the upper level D, which is broken by a screen section D¹, beyond which is a second closed section D² which terminates in a gate D³ overlying the gates C³ and B³. Beyond such gate is the closed section D⁴ which terminates in an inclined section D⁵, down which material may pass to the section D⁶, which is a continuation of or at the same level as the sections C¹ and C². This section is, in turn, broken by a gate D⁷ overlying the gate B⁵ in the lower deck. B⁶ terminates in a feed or chute D⁹ which leads down to the end of the lower deck B².

On the deck C¹, beyond the gate C³ is a V-shaped baffle E, the point of the V facing toward the stream of material as it passes from right to left, as shown in Figs. 1 and 2. This baffle deflects the material passing along C¹ to a pair of lateral conveyors E¹ and E², which lie on either side of the upper deck C and are supported upon the lower deck or by any suitable frame connection. E¹ and E² are each broken midway of their course by screen sections E³ E⁴, shown in detail in Fig. 4, and by the gates E⁵ E⁶, all three of which overlie a hopper E⁷, from the bottom of which are chutes E⁸ E⁹ leading to the discharge chutes B⁷ B⁸, respectively. The material may be passed down one or the other, under control of the swinging gate E¹⁰ or any other suitable means. At their lower ends E¹ and E² incline toward the central deck and their inturned ends E¹¹ E¹² feed material to the lower deck B adjacent its end, or to C.

Secured to and above the upper deck C in any suitable manner is a refuse trough, comprising an initial single section F which inclines to the right or left as at F¹ adjacent the baffle E and the upper ends of the troughs E¹ E². The section F² continues along one of such troughs, while the second section, F³, parallels the other trough E¹, these two sections converging as at F⁴ to join the single disposal section F⁵.

Material is fed into the whole device in any suitable manner, as for example through

the chute G. The two decks are reciprocated on the horizontal plane in opposition to each other, as for example through the rotating shaft H, the eccentrics H¹ H² thereupon, and the pitman H³ H⁴ secured to the upper and lower decks, respectively.

It will be realized that while I have illustrated a working device, the details thereof must be taken largely diagrammatically, and 10 many changes might be made in the number, shape, design, size and disposition of parts without departing from the spirit of my invention.

The use and operation of my invention 15 are as follows:

Any mixed material, and preferably run-of-the-mine coal, is fed upon the top deck or level, as shown in Fig. 1. The rotation of the driving shaft and the eccentrics thereupon gives an irregular conveying motion, which need not here be described, the result being that the material on the screen assembly passes from right to left, as shown in Figs. 1 and 2. If, for example, run-of-the-mine coal, of various and irregular sizes, is fed to the screen, it passes first over the screen D¹ in the upper level D. This is preferably a large mesh screen, for example of 3 inch mesh. All sizes of 3 inch pass thereover, while anything less than 3 inches drops through upon the screen C². This screen is a finer screen and through it pass the fines or slack to the bottom level B². The intermediate sizes pass along the second deck and through or over the screen C². If the gate C³ is closed, the intermediate grade is deflected by the baffle E to the side or picking screens E¹ E². The fines again pass through the screens E³ E⁴ and the 40 picked coal passes through or over the gates E⁵ E⁶ and is deflected back to the lower level B², as by the inwardly inclined portions E¹¹ E¹², or with slight modification, to the upper level. It then passes out over the 45 final chute B⁹, either to the conveyor B¹⁰ or to the car X, to which it may be loaded by any suitable means. While this picked, graded coal may be passed through the entire screen system and to the end track or conveyor, it may also be dropped to cars at 50 intermediate points. If the gates C⁸ and B³ are both left open, the graded coal passes, before picking, through the chute B⁶ to the car X³, together with the slack. Through 55 the gates E⁵ and E⁶ it may be passed down the chutes A⁸ and A⁹ to the car X¹ or X². The slack may similarly be discharged either at the end track or conveyor or to the intermediate tracks, through opening or 60 closing of the gates B³, B⁴ and B⁵. The lump coal bigger than 3 inch, or the size of the upper screen D¹, may be dropped through the gates D³, C³ and B³ directly to the chute B⁶ and the car X³, or it may pass 65 over the gate D³ when closed, and down the

incline D⁵, to the second level D⁶. The gate D⁷ furnishes means for dropping it through to the car X¹, and if that gate is closed it runs over the incline D⁹ and thus to the conveyor B¹⁰ and the car X.

It will thus be clear that to the first track car X³ either slack alone may be passed, or egg and slack, or run-of-the-mine, viz: all three grades. To the second car X² slack alone may be passed, or picked egg alone, 75 or picked egg and slack, or picked run-of-the-mine. To the car X¹ may be fed picked egg, picked 1 $\frac{1}{4}$ inch lump, picked 3 inch lump, picked run-of-the-mine, or slack. And a similar choice is open for feed to the 80 last car X.

Any suitable means, not herein shown, may be provided to support the pickers which pick the coal as it passes along the various screens. The large or 3 inch lump 85 may be picked directly into the section F¹ of the refuse trough. The branches F² and F³ take care of the picking troughs E¹ and E² over which passes the coal intermediate the 3 inch lump and the slack, and the section 90 5 conveys away the refuse picked from the various screens.

I claim:

1. A reciprocating screen comprising a central section and a plurality of side sections separate therefrom and adapted to be supplied with material therefrom:

2. A plural level reciprocating screen comprising a central section and a plurality of side sections separate therefrom and 100 adapted to receive material from an upper level of the screen and to return it to a lower level of said screen.

3. A plural level reciprocating screen comprising a central section and a plurality 105 of side sections separate therefrom and adapted to receive material from one level of the screen and to return it to another level of said screen.

4. A reciprocating screen comprising a 110 central section and a plurality of side sections separate therefrom and adapted to receive material therefrom, and a refuse trough adjacent and substantially parallel with each of said side sections.

5. A reciprocating screen comprising a central section and a plurality of side sections separate therefrom and adapted to be supplied with material therefrom, and a branched refuse trough one branch of which 120 is adjacent and substantially parallel with each of said side sections.

6. A reciprocating screen having a plurality of levels, a picking trough adjacent thereto and adapted to receive material 125 from one level of the screen and deliver it to another level thereof.

7. A reciprocating screen having a plurality of levels, a picking trough adjacent thereto and adapted to receive material 130

from one level of the screen and deliver it to another level thereof, and a screen surface intermediate the ends of said picking trough.

5 8. A reciprocating screen having a plurality of levels, a picking trough adjacent thereto and adapted to receive material from one level of the screen and deliver it to another level thereof, and a delivery chute and 10 gate therefor intermediate the ends of the picking trough.

9. A reciprocating screen having a plurality of levels, a picking trough adjacent thereto and adapted to receive material from 15 one level of the screen and deliver it to another level thereof, a screen surface intermediate the ends of said picking trough, and a delivery chute and gate therefor intermediate the ends of the picking trough.

20 10. A reciprocating screen assembly comprising upper and lower elements reciprocating in opposition to each other, adjacent picking troughs adapted to receive material from the upper element and deliver it to the 25 lower element.

11. A reciprocating screen assembly comprising upper and lower elements reciprocating in opposition to each other, and adjacent picking troughs adapted to receive material 30 from the upper element and deliver it to the lower element, said troughs being mounted upon and reciprocating with said lower element.

12. In a reciprocating screen, an upper 35 level and a lower level and adjacent picking troughs, and means for diverting material conveyed along the lower level to said picking troughs, and adjacent means for lowering the material conveyed along the 40 upper level to the lower level.

13. In a reciprocating screen, an upper level and a lower level and adjacent picking troughs, and means for diverting material conveyed along the lower level to said picking troughs, and adjacent means for lowering the material conveyed along the upper level to the lower level comprising a baffle across said lower level and a chute adjacent and beyond said baffle.

45 14. In a reciprocating screen, an upper level and a lower level and adjacent picking troughs, and means for diverting material conveyed along the lower level to said picking troughs, adjacent means for lowering the material conveyed along the upper level to the lower level, and aligned screens of varying mesh in said levels.

50 15. In a reciprocating screen, an upper level and a lower level and adjacent picking troughs, and means for diverting material conveyed along the lower level to said picking troughs, adjacent means for lowering the material conveyed along the upper level to the lower level, and aligned screens of 55 varying mesh in said levels, together with

aligned gates in said levels and means for opening and closing them independently.

16. A reciprocating screen assembly comprising upper and lower elements reciprocating in opposition to each other, the lower 70 element comprising a substantially continuous conveying surface, a plurality of gates therein, and means for opening and closing them independently, the upper element comprising a plurality of screening levels and 75 gates therein in line with the gates in the lower element.

17. A reciprocating screen assembly comprising upper and lower elements reciprocating in opposition to each other, the lower 80 element comprising a substantially continuous conveying surface, a plurality of gates therein and means for opening and closing them independently, said upper element comprising a lower level and a screen at 85 one end thereof and gates in line with the gates of the lower level, a baffle, and conveying means adapted to receive the material deflected by said baffle, an upper level overlying said lower level and adapted to 90 deliver said material to said lower level beyond said baffle.

18. A reciprocating screen assembly comprising upper and lower elements reciprocating in opposition to each other, the lower 95 element comprising a substantially continuous conveying surface, a plurality of gates therein and means for opening and closing them independently, said upper element comprising a lower level and a screen at 100 one end thereof and gates in line with the gates of the lower level, a baffle, conveying means adapted to receive the material deflected by said baffle, an upper level overlying said lower level and adapted to deliver 105 said material to said lower level beyond said baffle, a screen in the upper level overlying the screen in the lower, and gates in the upper level overlying the gates in the lower.

19. A reciprocating screen assembly comprising upper and lower elements reciprocating in opposition to each other, the lower element comprising a substantially continuous conveying surface, a plurality of gates therein and means for opening and closing them independently, said upper element comprising a lower level and a screen at one 110 end thereof and gates in line with the gates of the lower level, a baffle, and conveying means adapted to receive the material deflected by said baffle, comprising a picking trough substantially parallel with said lower element and reciprocating therewith.

20. A reciprocating screen assembly comprising upper and lower elements reciprocating in opposition to each other, the lower element comprising a substantially continuous conveying surface, a plurality of gates therein and means for opening and closing them independently, said upper element 125

- comprising a lower level and a screen at one end thereof and gates in line with the gates of the lower level, a baffle, conveying means adapted to receive the material deflected by said baffle, comprising a picking trough substantially parallel with said lower element and reciprocating therewith, and a screen surface intermediate the ends of such trough.
10. 21. A reciprocating screen comprising a central section and a plurality of separate side sections adapted to receive material

therefrom and to return it to the central section.

22. A reciprocating screen comprising a central section and separate side sections adapted to receive material deflected from the central section and adapted to deliver the material back to the central section.

Signed at Pittsburgh, county of Allegheny and State of Pennsylvania, this 16th day of February, 1922.

ROBERT WILLIAM JOHNSON.
